UNITED STATES PATENT OFFICE.

AUSTIN F. JACKSON, OF TAUNTON, MASSACHUSETTS.

DESIGN FOR A TEA OR COFFEE POT.

SPECIFICATION forming part of Design No. 21,331, dated February 2, 1892.

Application filed December 5, 1891. Serial No. 414,170. Term of patent 14 years.

To all whom it may concern:

Be it known that I, AUSTIN F. JACKSON, a citizen of the United States, residing at Taunton, in the county of Bristol and State of Massachusetts, have invented and produced a new and original Design for Tea or Coffee Pots, of which the following is a specification, reference being had to the accompanying drawings, showing a part thereof.

10 Figure 1 is a side view of a coffee-pot constructed in accordance with my design, and Fig. 2 is a plan view of the same.

The leading feature of my design is the external shape or contour of the body portion.

15 A is a circular base bounding the margin of a flat bottom. From this base the body portion curves outwardly to its largest diameter at a and then inwardly at about the middle of its height, then outwardly again at 20 b, but to a smaller diameter than at a, and then it curves inwardly again and terminates at the top with an outwardly-flared and irregular lip c. Through the vertical height of the body there extends upon each side two creases 25 or indentations d d, which are located the same distance apart, so as to divide the body into quarters. Between the creases and extending from the marginal lip c downwardly over the plain surface is a raised floral ornament e. At the base of the body portion there are scrolled legs f, terminating in claw-shaped feet f'.

30 B is the top, which is somewhat conical in shape; but instead of having straight sides its sides are curved first inwardly and then outwardly in waved lines harmoniously with the walls of the body portion, the top being 35 surmounted by an ornamental knob or finial k.

C is the handle, which joins the body portion of the pot just below the upper lip c and 40 also at the point of greatest diameter below, its points of union being expanded or swelled and provided with a floral ornament i. The body of the handle is creased or fluted longitudinally and provided with slight ornamental 45 scrolls j.

D is the spout, which has a very wide base joining onto the part of the body having the greatest diameter and rising to the top of the body portion with a gradual taper and a reverse curve. Upon the base of the spout is displayed in relief a scrolled ornament l.

What I claim is—

1. The design for the shape of a tea or coffee pot, substantially as shown and described. 55

2. In a design for a tea or coffee pot, as herein shown and described, the handle provided with the floral ornaments i i at its points of union with the body and fluted longitudinally at intermediate points and having ornamental scrolls j j applied thereto, as shown. 60

3. In a design for a tea or coffee pot, as herein shown and described, the spout having upon its wide lower end a scrolled ornament l in relief, as shown. 65

4. In a design for a tea or coffee pot, as herein shown and described, the lid of a generally-conical shape with waved sides surmounted by the ornamental finial k, as shown.

AUSTIN F. JACKSON.
